(57) **CLAIM**

The ornamental design for a controller with screen, as shown and described.

DESCRIPTION

FIG. 1 is a front perspective view of a controller with screen showing my new design;

FIG. 2 is a bottom perspective view thereof;

FIG. 3 is a front elevation view thereof;

FIG. 4 is a rear elevation view thereof;

FIG. 5 is a first side elevation view thereof;

FIG. 6 is a second side elevation view thereof;

FIG. 7 is a bottom plan view thereof; and,

FIG. 8 is a top plan view thereof.

References to "side", "top", "front", "rear" and "bottom" in the figure descriptions are not meant to require certain in-use orientation; a controller with screen according to the claimed design may be used in any orientation.

The broken lines in the drawings depict environmental matter and form no part of the claimed design.
